(57) **CLAIM**

The ornamental design for a tweezer, as shown and described.

DESCRIPTION

FIG. 1 is a front, right, and top perspective view of a tweezer, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of an area labeled 8 in FIG. 1 comprising a protrusion.

The dash-dot-dash broken lines illustrate the boundary around the partial view and form no part of the claimed design.
